126 STOVES & FIREPLACES
Cooking stoves

Design for a Cook Stove

Des. No 2319.

Patented May 3, 1866.

2,319.—Plates of a Cook Stove.—Samuel Granger,
Albany, N. Y.

Front view

Q.S. 2319

Samuel H. Kaneson of Albany, N.Y.

Letters Patent No. 2319 Dated May 15, 1861

Design for the plates of a cook stove.

The schedule referred to in these Letters Patent and marking part thereto.

None of which may concern.

Be it known that I, Samuel H. Kaneson, of the City of Albany, and County of Albany, State of New York, have invented or produced a new and original design for the plates of a cook stove; and I do hereby declare that the following is full and exact description of the same, reference being made to the accompanying plates, which

A represents the design for the front;

B " " " front door;

C. E. " " " oven doors;

D " " " fire door.

Together forming plates for Cook's Stove "Gaud-Cheer."

I claim as new and desire to secure by Letters Patent

Design for plates of cook stove as now and described in schedule

Geo. D. Burton
